FOLDING TABLE WITH SPRING LATCH MECHANISM

Dale J. Clapper, Meyersdale, Pa.

Application December 16, 1955, Serial No. 553,512

4 Claims. (Cl. 311—87)

The present invention relates to a novel and improved multipurpose table characterized by folding legs and which, although it is primarily intended to serve as a folding banquet table, is versatile in nature and is therefore susceptible of use under many and varying circumstances as a barbecue lawn table, school or office conference table, and so on.

Tables for use as above stated and for similar miscellaneous purposes are, as is well known, subjected to rough handling and usage and are often called upon to support heavy loads. Therefore, it is an object of the invention to structurally, functionally and otherwise improve upon similarly constructed and performing prior art folding tables and, in doing so, to provide a construction which is simple, practical, easy to handle and store, is intended to meet with widespread adoption and use, complies with manufacturing economies of manufacturers and is such that it will serve the expected needs of all classes of users.

In carrying out the preferred embodiment of the overall inventive concept, novel leg-frames are employed. These are preferably constructed from proper gage steel tubing electrically welded and fastened to cross members of frame means on the underneath side of the table top by clevises, U-bolts or hook-bolts so that there is little danger of the leg-frames becoming loose and also so that the nuts on the bolts may be tightened up to offset any tendency of the parts becoming loose and wobbly.

Novelty is predicated on duplicate, hingedly mounted folded leg-frames each equipped with a substantially U-shaped or an equivalent stay member. The stay members are hingedly connected to the legs of the respective leg-frames and the leg-frames fold against the underneath side of the table so that the stay members overlap and are sandwiched between the leg frames and said underneath side, whereby to promote compactness and convenience and to insure satisfactory retention of the parts in their folded position.

Then, too, novelty is also predicated on the arrangement of parts above referred to wherein latch-equipped brackets or fixtures are secured to the frame means on the underneath side of the table, these being in alignment with each other and longitudinally spaced apart and so constructed that they function, somewhat semi-automatically, in reliably and securely retaining the leg-frames and stay members in both open and closed positions.

In addition to the above, the individual latch-equipped fixtures are novel in that each fixture is characterized by a base plate with specially designed flanges having keeper notches, inclined leading edges on the flanges, and a latch lever with a suitably and properly bent tang which not only serves to securely maintain the bight portions of the U-shaped stay members in place, but facilitates the engagement thereof with the keeper notches.

Other objects, features and advantages will become more readily apparent from the following description and the accompanying sheets of drawings.

2

In the accompanying drawings, wherein like numerals are employed to designate like parts throughout the same:

Figure 1 is a perspective view of the improved folding banquet table constructed in accordance with the principles of the invention and showing the same set up in use.

Figure 2 is a view which is partly in section and partly in elevation and which is fragmentarily shown and taken approximately on the plane of the line 2—2 of Figure 1 looking in the direction of the arrows, said view showing the leg-frames in partial collapsed positions in dotted lines.

Figure 3 is a bottom plan view with the parts collapsed or completely folded.

Figure 4 is a fragmentary bottom plan view of one of the latch-equipped fixtures.

Figure 5 is a longitudinal section through the same.

Referring now to the drawings with the aid of reference numerals and lead lines, the table top, which is of elongate or rectangular form, is denoted generally by the numeral 6. In practice, this may be of any suitable material. It is here shown with a depending marginal skirt or frame denoted generally by the numeral 8 in Figure 3 and said frame has a longitudinal strip member 10 and transverse cross members 12 spaced inwardly from the transverse end members of the frame 8. The numeral 14 in Figure 3 designates a first leg-frame, while the numeral 16 designates a second leg-frame. The numeral 18 designates a first substantially U-shaped stay member carried by the leg-frame 14 and the numeral 20 designates a second U-shaped stay member carried by the second leg-frame 16. These parts are duplicates of one another, and a description of the leg-frame 14 and its stay member 18 will suffice. To this end, each leg-frame comprises a pair of legs 22 having spaced parallel upper portions and outwardly and downwardly flaring lower end portions terminating in rubber or equivalent feet or protectors 24. Disposed at right angles to the upper ends of the legs is a frame member 26 which may be referred to as a shaft, and it will be noticed that this is substantially of the same length as the cross-member

12. In fact, it bears against one longitudinal surface thereof and is cylindrical in cross-section and the end portions are journaled for oscillation in the saddle portions of the U-shaped bolts or clevises 28. Hook-bolts, not shown, may be substituted for the U-bolts. It should be noted that the leg-frames or pedestals being thus mounted permit the legs to be readjusted if they should become loose or wobbly from being folded and unfolded over many years of use. The divergent lower end portions of the legs are provided with a cross-brace 30. The parallel portions are provided with selectively usable bolt holes 32 and these serve to accommodate the screw-threaded, laterally directed terminal ends of the limbs

34 of the adjacent stay member 18 or 20, as the case may be. The bight portions of the respective stay members are denoted by the numerals 36, and these are adapted for direct releasable or latching engagement with the latch-equipped devices or fixtures which are attached at longitudinally spaced points to the rail or frame member 10.

For convenience, the left-hand or so-called first fixture is denoted by the numeral 38 while the second, correspondingly constructed fixture is denoted by the numeral 40. Both fixtures are the same in construction, and a description of one will suffice for both. To this end, each fixture as shown in Figures 4 and 5 comprises a base plate 42 which is fastened by screws or the like 44 to the underneath side of the table, more particularly the rail 10. The plate is substantially rectangular and is provided along its longitudinal edge portions with a pair of lateral

flanges 46 disposed in parallelism. The leading end of the plate is beveled as at 48 and the adjacent leading edges of the flanges are beveled or inclined as at 50. These serve to pilot the bight portions 36 into the keeper notches 52 provided therefor inwardly of the inclined surfaces 50. The notches may be shaped as shown in Figure 5 to facilitate releasing of the bight portion in an obvious manner. Inwardly of the keeper notches there is a truncated conical abutment or stop 54 for the lever latch 56. This latch is shaped as shown in Figure 4 and is provided with spaced parallel ears 58 which are hingedly pinned as at 60 to the cooperating flanges 46. One end portion 62 is fashioned into a finger piece and this is provided with a boss 64 which cooperates with the boss 66 on the base plates to accommodate a compression coil-type spring 68 which serves to spring-bias the latch lever so that the end portion 70 serves to maintain its bight portion 36 securely seated in the keeper notches 52. The right-hand tip of the latch or lever is also flared and rounded and suitably shaped as at 70 to cooperate with the inclined piloting surfaces 50 in feeding the bight portions into the keeper notches. This is the aforementioned semi-automatic feature.

When the table is set up for use as shown in full lines in Figures 1 and 2, it will be evident that the leg-frames 14, stay member 18, and first fixture 38 cooperate with each other. That is to say, the stay member is latched to the fixture and the legs are held in erected position as is obvious. The same is true in respect to the so-called second leg-frame 16, its stay member 20, and its companion fixture 40. It is important to note, however, that these fixtures are so spaced in relation to the length of the stay members 18 and 20 that they also have a second function, perhaps the primary function of the invention. That is to say, when the leg-frames 14 and 16 are folded against the underneath side of the table, the stay members 18 and 20 change their position. The bight portion of the stay member 18 is now engaged with the remote fixture 40 and the bight portion of the stay member 20 is engaged with the remote fixture 38. This causes the stay members to overlap with their limbs crossed in the manner shown to provide the desired feature of compactness and convenience depicted in Figure 3.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A folding table comprising a table top, a first leg-frame having one end thereof hingedly attached to the underneath side of said top adjacent to one end portion of said top, a second leg-frame, complementary to said first leg-frame, having a corresponding one end thereof independently and hingedly attached to said underneath side adjacent to the other end portion of said top, said leg-frames being folded up and into close, substantially coplanar relationship with each other and assuming out-of-the-way positions in proximity to said underneath side but being swingable down and away from each other and said top to depending table top supporting positions when desired, a stay member pivotally attached at one end to each leg-frame, the respective stay members being disposed in overlapping relation and being compactly sandwiched between said underneath side and said leg-frames, and latch-equipped means fixed to said underneath side, adjacent ends of said stay members being releasably connected to said latch-equipped means, said stay members being substantially U-shaped in construction, the intermediate portions of their respective limbs being disposed in crossed relation, said latch-equipped means comprising a pair of longitudinally spaced fixtures, one stay member

5 having its free end portion releasably latched to that fixture which is remote therefrom, and the free end of the other stay member being likewise releasably latched to the other fixture which is also remote therefrom.

2. A folding table comprising a table top, a first leg-frame having one end thereof hingedly attached to the underneath side of said top adjacent to one end portion of said top, a second leg-frame, complementary to said first leg-frame, having a corresponding one end thereof independently and hingedly attached to said underneath side adjacent to the other end portion of said top, a first latch-equipped fixture fixed to said underneath side adjacent to said first leg-frame, a first stay member having one end portion pivotally connected to the legs of said first leg-frame, the other free end portion being releasably connectible with said fixture, a second latch-equipped fixture longitudinally spaced from and fixed to said underneath side in line with said first fixture but adjacent to said second leg-frame, a second stay member like said first-named stay member having one end pivotally connected to the legs of said second leg-frame, the other end thereof being free and releasably connectible with said second fixture, the distance between said fixtures being predetermined and proportional with the length of said stay members, 10 whereby the free end of the second stay member is releasably connectible with the first fixture and the free end of the first stay member is releasably connectible with said first fixture when the leg-frames are folded against said underneath side, each stay member being substantially U-shaped and embodying a pair of limbs connected at their same ends by way of a bight portion, the other ends of said limbs being pivotally, detachably and adjustably connected with the intermediate portions of their respective companion legs, each fixture comprising a bracket 15 having keeper notches for the bight portion of the co-operating stay member, and a manually actuatable spring-biased latch pivoted on said bracket in a manner to retain the stated bight portion in its intended keeper notches.

3. A table construction comprising a top having a flat 20 underneath side with frame means embodying at least one fixed cross-member, a leg-frame having a pair of coplanar closely spaced legs connected at their upper ends to a central portion of a right angularly disposed linearly straight frame member cylindrical in cross-section and of a length approximately equal to the length of said cross-member and abutting a cooperating lengthwise surface of said cross-member, U-bolts adjustably and detachably mounted on said cross-member and embracing and hingedly, detachably and adjustably connecting the respective end portions of said frame member to said cross-member, a U-shaped stay member embodying limbs pivotally and adjustably attached to and carried by said legs, and latch means fixed to said underneath surface and serving to accommodately retain said stay member in either folded or erected position, said latch means embodying at least one fixture having a base plate fastened to said underneath side, said plate having depending spaced parallel flanges with opposed inclined leading edge portions, opposed keeper notches formed in the intermediate portions of said flanges and cooperating in operative association with their respective leading edges, a spring-biased latch lever opposed to said plate and pivotally mounted for operation between said flanges, said lever having a finger-piece at its spring-biased end and tang at its other end, the tip of said tang being flared away from said base plate and constituting a cam and cooperating with said inclined leading edges, and said stay member being U-shaped and having a bight portion which is located and adapted to ride along said leading edges in a manner to engage said cam, lift the latch lever and seat itself in said keeper notches.

4. A table construction comprising a top, a transverse cross member secured to the underneath side of said top, a leg frame embodying a linearly straight frame member 25 abutting and detachably, adjustably and hingedly attached

to said cross member, a pair of closely adjacent legs affixed to and extending laterally from an intermediate portion of said frame member, a U-shaped stay member embodying limbs pivotally and adjustably attached to said legs, the opposite ends of said limbs being connected by an integral bight portion, the latter extending beyond the adjacent lower ends of said legs when the legs and stay member are collapsed into folded out-of-the-way positions beneath and in close proximity to the underneath side of said table top, a first latch-equipped fixture secured to the underneath side and embodying a manually releasable latch and cooperating keeper notches with which said bight portion is connected temporarily, and a second latch-equipped fixture longitudinally spaced from and also fixed to the underneath side of the table top in longitudinal alignment with said first named fixture and situated between the limbs of said stay member and said legs when the latter are in the aforementioned folded positions and embodying keeper notches and a latch for the stated bight portion, the openable and clos-

able tip ends of said latches facing each other whereby both latch-equipped fixtures serve the same stay member depending upon whether said leg frame is folded to an out-of-the-way position or swung out and down to its

5 table erecting position.
